Inventor

UNITED STATES PATENT OFFICE

HARRY H. EVERHARD, OF CANTON, OHIO

SCREEN-FRAME CONSTRUCTION

Application filed April 9, 1929. Serial No. 353,808.

The invention relates to window screens such as are used for ventilating purposes or as fly screens, and more particularly to an adjustable screen having a metal frame arranged to be located in an open window or similar place.

In the past, adjustable screens have usually been made having wooden frames. Such a construction presents difficulties if the wooden frame becomes damp or wet, because of moisture in the atmosphere from abnormal humidity, dew, or because of rain storms. The dampness or moisture is absorbed by the wooden frames causing the same to swell, thus preventing free adjustment of the screen, and sometimes preventing any adjustment whatsoever.

These difficulties have been overcome in the past by constructing screen frames of sheet metal which is substantially unaffected by weather conditions. In order that metal frame construction be satisfactory, free sliding action between the several adjustable frame members must be provided for, and means for clamping a screen fabric to the metal frame must be provided.

However, the production of a screen having a metal frame provided with the desired structural characteristics has been so expensive that such metal frame screens have not been able to compete on the open market with screens having wooden frames.

My prior Patent No. 1,614,191 of January 11, 1927 discloses metal frame screen construction which has the desired characteristics, but when shipping or using such screens, the channels and edges providing the sliding edge contact between the two frames may become bent or dented because of being jammed or bumped in shipping or because of falling on a corner or an edge when being installed for use. Such denting, damage or injury to the channel and flange elements may prevent the screen frames from being easily or properly adjusted.

My prior Patent No. 1,695,091 of December 11, 1928 discloses metal frame screen construction in which these difficulties are overcome, and in which both metal frames are the

product of the same forming rolls, thus being similar in cross section.

The screen frame construction of the latter patent, however, does not have a continuous free edge sliding contact between the frames which is a most desirable feature of my former patent. The construction of my latter patent also includes various accessory parts, clips and rods necessary for completely assembling the screen.

Because of the large number of pieces used in the construction of screen frames such as shown in my prior patents, the cost of producing the same is considerably greater than the cost of producing screens having wooden frames.

The object of the present invention is therefore to provide a metal frame screen having a very small number of parts; to provide a screen having a cost of construction equal to or less than wooden frame screens; to provide a screen having a free sliding edge contact between the adjustable constituent frames, which edge contact construction is protected from injury or damage in shipping or in use; to provide a screen having rounded corners and having a neat and smooth appearance; and to provide a screen having sufficient frame strength to withstand the shocks and strains imposed upon the screen without the use of rods for reinforcement and for clamping the screen fabric to the frame.

These and other objects may be attained by a construction in which the constituent adjustable frames are each composed of three parts, namely: a frame bar bent to form three sides of the screen frame, an end bar clamped by the frame bar to form the fourth side of the frame, and screen fabric clamped directly by and between portions of the frame bar and end bar.

Moreover, the objects of the invention are attained by providing a construction in which the frame bars of both constituent frames are the product of the same forming rolls and have substantially the same cross sectional arrangement; and in which the end bars are made from the same stock material.

being only slightly modified in shape during assembly.

An embodiment of the invention is illustrated in the accompanying drawings in which

5 Figure 1 is a front elevation of the improved adjustable screen;

Fig. 2, a plan view of a mitred strip from which the frame bar of one of the constituent frames is formed;

10 Fig. 3, a plan view of a mitred strip from which the frame bar of the other constituent frame is formed;

Fig. 4, an elevation of a frame bar partially 15 formed from the strip shown in Fig. 2;

Fig. 5, an elevation of a frame bar partially formed from the strip shown in Fig. 3;

Fig. 6, an enlarged section taken as on the line 6—6, Fig. 4;

20 Fig. 7, an enlarged section taken as on the line 7—7, Fig. 5;

Fig. 8, an enlarged section showing the manner in which screen fabric is clamped by the frame bar shown in Figs. 4 and 6, and 25 taken as on the line 8—8, Fig. 1;

Fig. 9, an enlarged section showing the manner in which screen fabric is clamped by the frame bar shown in Figs. 5 and 7, taken as on the line 9—9, Fig. 1;

30 Fig. 10, an enlarged section showing the sliding edge contact connection between constituent frames having frame bars shown in Figs. 8 and 9, and taken as on the line 10—10, Fig. 1;

35 Fig. 11, an enlarged elevation of one corner portion of one of the constituent frames;

Fig. 12, an enlarged elevation of one corner portion of the other constituent frame;

40 Fig. 13, a fragmentary elevation of screen fabric having angularly cut corners, showing the same ready to be clamped by an end bar;

Fig. 14, an elevation of an end bar ready to 45 be attached to the screen fabric shown in Fig. 13;

Fig. 15, a fragmentary elevation showing the end bar and screen fabric attached together ready to be clamped by the frame bar;

50 Fig. 16, a fragmentary elevation showing the fabric and end bar assembled with and clamped by the frame bar;

Fig. 17, a section through one end portion of an end bar as on the line 17—17, Fig. 15;

55 Fig. 18, a cross section through an end bar as on the line 18—18, Fig. 14;

Fig. 19, a cross section showing the screen fabric attached to the end bar as on the line 19—19, Fig. 15; and

60 Fig. 20, a sectional view showing the manner in which the end bar is clamped by the frame bar taken as on the line 20—20, Figs. 1 and 16.

Similar numerals refer to similar parts throughout the drawings.

65 The screen consists of two frame sections

A and B, which are slidably connected together so that the screen as a whole may be adjusted longitudinally in order that the same may be placed in window frames of varying width.

The frame A consists generally of a frame bar 21, an end bar 22 and screen fabric 23; while the frame B consists of the frame bar 24, the end bar 25 and the screen fabric 26.

The frame bars 21 and 24 are preferably 75 formed from metal strips 27 and 27^a respectively. The continuous strip 27 is preferably first mitred at 28 and 29 at two places along its length where two corners of the screen frame are later to be formed. The mitred strip 27 is then passed through a series of rolls to form the strip into the shape shown generally at 30 in Fig. 6, which in cross section may be channel-shaped, including a web 31, and flanges generally indicated at 32 and 33.

The substantially Z-shaped flange 32 may consist of a downturned portion 34 extending from the web 31, an outturned portion 35 forming a convex angle as at 36 with the downturned portion 34, and an outwardly downturned portion 37 extending from the outturned portion 35 to form the concave angle 38.

The substantially Z-shaped flange 33 may include an inwardly downturned portion 39, an outwardly downturned portion 40, a second inwardly downturned portion 41, an outturned portion 42 and a downturned portion 43. The convex angle 44 is formed between the portions 39 and 40, the concave angle 45 being formed between the portions 40 and 41, and the convex and concave angles 46 and 47 being formed respectively between the portions 41 and 42, and the portions 42 and 43, all as shown in Fig. 6.

Similarly, the strip 27^a may be mitred at two places along its length as at 48 and 49 and the strip may then be passed through the same series of forming rolls through which the strip 27 was passed. In carrying out the forming operation on the strip 27^a, the same is shifted sidewise relative to the rolls so that the resulting channel formation will be shifted relative to the width of the strip to produce the channel shape shown generally at 50 in Fig. 7.

This channel shape may include a web 51 and flanges 52 and 53. The flange 52 may be composed of a downturned portion 54, an outturned portion 55, forming with the portion 54 the convex angle 56. The outwardly downturned portion 57 forms a concave angle 58 with the outturned portion 55 and is then upwardly and outwardly curved half round as at 59, and ends in the upwardly inturned portion 60 which extends substantially parallel with the outwardly downturned portion 57.

The flange 53 may consist of an inwardly 120

downturned portion 61, an outwardly downturned portion 62, a second inwardly downturned portion 63 and the turned edge 64. Convex and concave angular bends are formed between the several portions 61, 62, 63 and 64 of the flange 53 as at 65, 66 and 67, all as shown in Fig. 7 of the drawings.

The strips 27 and 28 are so positioned in passing through the series of forming rolls that the resulting channel shapes 30 and 50 will have the mitre portions 28 and 29, and 48 and 49 registering as shown generally at 68 and 69 respectively in Figs. 4 and 5; and so that the various convex and concave angles in cross section form continuous ribs and grooves throughout the length of the strips.

The portions 31, 34, and 39 of the shape 30, and portions 51, 54 and 61 of the shape 50 thus form a box channel; and the registering mitre portions 68 and 69 extend only to the box channel as shown at 70 and 71 in Figs. 4 and 5.

The box channel of each shape 30 and 50 is then bent inward so as to bring the mitred edges together to form three sides of the rectangular frame sections A and B having corners 72 and 73 well shown in Figs. 11 and 12. The formation of the corners 72 and 73 is strong and smooth without having any exposed edges of sheet metal and corresponds to the corner construction disclosed in my Patent No. 1,695,081, of December 11, 1928.

In assembling the frame A, the screen fabric 23 thereof has its corners angularly cut off as shown at 74 in Figs. 1 and 13. The 35 end portion 75 of the fabric is then engaged between the parallel portions 76 of the U-shaped end bar 22 after which the end bar is bent angularly having a flange portion 77 to permanently secure the screen fabric to the 40 end bar as is well shown in Fig. 19.

Each end portion 78 of the end bar is then formed with a flange 79 and angular portions 80 and 81 as shown in Figs. 15 and 17.

The end bar 22 with the screen fabric 23 secured thereto is then slid longitudinally into the partially completed three-sided frame above described. The frame may then be placed in a suitable press which is operated to press the flanges 32 and 33 together 50 to securely clamp the screen fabric 23 between the flanges in a manner shown in Fig. 8. During this pressing operation, the flange 32 is bent inward toward the flange 33 so that the convex angle 36 engages the screen fabric 23 within the concave angle 45 of the flange 33. At the same time, the convex angle 46 of the flange 33 engages the screen fabric against the concave angle 38 of the flange 32. The screen fabric is thus securely clamped by the 60 ribs and grooves of the frame bar flanges without the use of any special clamp or clamping rods.

Meanwhile, the end bar 22 is secured by the frame bar 21 with the flange portion 78 securely clamped between the portions 31, 34

and 39 of the frame bar 21 in a manner shown by Fig. 20.

In a similar manner the screen fabric 26 may be securely clamped by the frame bar 24 by pressing the flanges 52 and 53 thereof together, the fabric being secured by the angles 56, 58, 66 and 67; and the end bar 25 will have its end flanges 78 securely clamped by the portions 51, 54 and 61 of the frame bar 24 to form the frame section B all as shown in Figs. 9 and 20.

The end bar 25 of the frame section B is similar in all respects to the end bar 22 of the frame section A excepting that the flange 77 thereof is turned in a direction opposite to the flange 77 of the end bar 22 as shown in Fig. 20 so as to limit the opening movement of the assembled screen.

The two frame sections A and B are then slidably engaged together to produce the adjustable screen shown in Fig. 1, by longitudinally sliding the portion 43 of the frame bar 21 within the U-shaped channel formed by the portions 57, 59 and 60 of the frame bar 24. This sliding engagement between the two screen frames A and B is a sliding edge contact similar in some respects to a sliding edge contact shown in my prior Patent No. 1,614, 191 of January 11, 1927 excepting that the portions forming the same are not at the extreme edges of the screen, but are protected from injury and damage by being located along the inner adjacent edges of the frame bars 21 and 24.

The resulting adjustable screen is thus provided with a free sliding edge contact between the constituent frames, with the end bar and frame bar of each frame section securely clamped together, and with the screen fabric positively clamped and locked by the flanges 105 of the frame bar and end bar without the use of special clips or rods and without performing the screen fabric.

Likewise, the screen may be quickly and easily produced at a cost equal to or less than the cost of producing wooden frame screens, and the screen has smooth rounded corners, and a very neat appearance.

And finally the screen is composed of only six parts, two frames each having a frame bar, an end bar and screen fabric.

I claim:

1. A screen including a frame, and screen fabric, the frame including a one-piece sheet metal, channel-bar having a web and substantially Z-shaped flanges extending inwardly therefrom forming a plurality of box channel frame side members, and the screen fabric being secured between and clamped by the Z-shaped flanges of the channel-bar.

2. A screen including a frame, and screen fabric, the frame including a one-piece sheet metal, channel-bar forming a plurality of the frame side members, the channel-bar in

- cluding a web and flanges extending inwardly therefrom to form a box channel, there being a rib formed in one flange and a groove formed in the other cooperating with the rib, and the screen fabric being located between the flanges and secured between and clamped by the rib and groove.
3. A screen including a frame, and screen fabric, the frame including a one-piece sheet metal channel-bar forming a plurality of the frame side members, the channel-bar including a web and flanges extending inwardly therefrom to form a box channel, there being a rib and groove formed in one flange and a groove and rib formed in the other cooperating therewith, and the screen fabric being located between the flanges and secured between and clamped by the ribs and grooves.
4. A screen including a frame, and screen fabric, the frame including a one-piece sheet metal channel-bar having a web and substantially Z-shaped flanges extending inwardly therefrom forming three box channel frame side members, and an end bar forming the fourth frame side member, the end bar being secured between and clamped by the Z-shaped flanges of the channel-bar, and the screen fabric secured at three edge portions between and clamped by the Z-shaped flanges of the channel-bar and secured at its fourth edge portion by and clamped by the end bar.
5. A screen including a frame, and screen fabric, the frame including a one-piece sheet metal channel-bar forming three of the frame side members, and an end bar forming the fourth frame side member, the channel-bar including a web and flanges extending inwardly therefrom to form a box channel, there being a rib formed in one flange and a groove formed in the other cooperating with the rib, the end bar being secured between and clamped by the flanges of the channel-bar, and the screen fabric being located at three edge portions between the flanges and secured between and clamped by the rib and groove and secured at its fourth edge portion by and clamped by the end bar.
6. A screen including a frame, and screen fabric, the frame including a one-piece sheet metal channel-bar having a web and substantially Z-shaped flanges extending inwardly therefrom forming three box channel frame side members, and an end bar forming the fourth frame side member, the channel-bar including a web and flanges extending therefrom, end flanges on the end bar, the end flanges being secured between and clamped by the channel-bar web and Z-shaped flanges, and the screen fabric secured at three edge portions between and clamped by the Z-shaped flanges of the channel-bar and secured at its fourth edge portion by and clamped by the end bar.
7. A screen including a frame, and screen fabric, the frame including a one-piece sheet metal channel-bar having a web and substantially Z-shaped flanges extending inwardly therefrom forming three box channel frame side members, and a U-shaped channel end bar forming the fourth frame side member, the end bar being secured between and clamped by the Z-shaped flanges of the channel-bar, and the screen fabric secured between and clamped by the Z-shaped flanges of the channel-bar and the end bar.
8. An adjustable screen comprising a pair of sheet metal frame sections, each frame section including a one-piece channel-bar having a web and substantially Z-shaped flanges extending inwardly therefrom forming a plurality of box channel frame section side members, and screen fabric secured between and clamped by the Z-shaped flanges of the channel-bar.
9. An adjustable screen comprising a pair of sheet metal frame sections, each frame section including a one-piece channel-bar forming a plurality of the frame section side members, each channel bar including a web and flanges extending inwardly therefrom to form a box channel, one of the flanges of one of the channel-bars having a rounded U-shaped channel extending therefrom, one of the flanges of the other channel bar having its free edge portion slidably engaged in sliding contact with the bottom of the U-shaped channel, and screen fabric for each frame section secured between and clamped by the flanges of the frame section channel-bar.
10. An adjustable screen comprising a pair of sheet metal frame sections, each frame section including a one-piece channel-bar having a web and substantially Z-shaped flanges extending inwardly therefrom forming three box channel frame section side members, and an end bar forming the fourth frame section side member secured between and clamped by the Z-shaped flanges of the channel-bar and screen fabric for each frame section secured at three edge portions between and clamped by the Z-shaped flanges of the frame section channel-bar and secured at its fourth edge portion by and clamped by the end bar.
11. An adjustable screen comprising a pair of sheet metal frame sections, each frame section including a one-piece channel-bar having a web and substantially Z-shaped flanges extending inwardly therefrom forming three box channel frame section side members, and an end bar forming the fourth frame section side member secured between and clamped by the Z-shaped flanges of the channel-bar, screen fabric for each frame section secured at three edge portions between and clamped by the Z-shaped flanges of the channel-bar and secured at its fourth edge portion by and clamped by the end bar.

of the frame section channel-bar and secured at its fourth edge portion by and clamped by the end bar, and flanges on the end bars limiting the opening movement of the screen.

5 In testimony that I claim the above, I have hereunto subscribed my name.
